(57) CLAIM

The ornamental design for a door for a merchandise display, as shown and described.

DESCRIPTION

FIG. 1 is a right front perspective view of a door for a merchandise display showing my new design;

FIG. 2 is a left rear perspective view thereof;

FIG. 3 is a front elevational view thereof;

FIG. 4 is a right end view;

FIG. 5 is a left end view;

FIG. 6 is a top end view;

FIG. 7 is a bottom end view;

FIG. 8 is a rear elevational view thereof;

FIG. 9 is a right front perspective view of an alternative door for a merchandise display showing my new design;

FIG. 10 is a left rear perspective view thereof;

FIG. 11 is a front elevational view thereof;

FIG. 12 is a right end view;

FIG. 13 is a left end view;

FIG. 14 is a top end view;

FIG. 15 is a bottom end view;

FIG. 16 is a rear elevational view thereof;

FIG. 17 is a right front perspective view of another alternative door for a merchandise display showing my new design;

FIG. 18 is a left rear perspective view thereof;

FIG. 19 is a front elevational view thereof;

FIG. 20 is a right end view;

FIG. 21 is a left end view;

FIG. 22 is a top end view;

FIG. 23 is a bottom end view;

FIG. 24 is a rear elevational view thereof;

FIG. 25 is a right front perspective view of yet another alternative door for a merchandise display showing my new design;

FIG. 26 is a left rear perspective view thereof;

FIG. 27 is a front elevational view thereof;

FIG. 28 is a right end view;

FIG. 29 is a left end view;

FIG. 30 is a top end view;

FIG. 31 is a bottom end view; and,

FIG. 32 is a rear elevational view thereof.
